ABSTRACT

A mobile frame including a generally frusto-conical ground wheel journalled for rotation about a generally horizontal but inclined transverse axis with the lower periphery of the wheel in surface-to-surface contact with the ground and the minor and major diameter ends of the wheel open and closed, respectively. Stone deflecting structure is positioned outwardly of the open minor diameter side of the wheel for deflecting windrowed stones into the lower periphery of the open side of the wheel and the interior of the wheel includes generally radially extending paddles supported from the closed end of the wheel and provided for elevating stones collected in the lower peripheral portion of the wheel in response to rolling movement of the wheel over the ground. Also, a stone retaining shield is provided to prevent discharge of the stones from the open side of the wheel until they have been elevated to a predetermined level and gathered stone receiving structure is supported at the aforementioned level for receiving the stones discharged outwardly of the open side of the wheel by the paddles.

STONE GATHERER

The stone gatherer of the instant invention has been specifically designed to provide a means whereby windrowed stones may be readily picked from the ground. Although the gatherer of the instant invention may be readily incorporated into a stone windrowing machine, in order to simplify the invention, it is specifically illustrated and described hereinafter merely as a stone picking up machine for gathering previously windrowed stones.

The main object of this invention is to provide a stone gathering machine of simple construction and efficient in picking up windrowed stones whereby stones may be picked up from cultivated land at a reasonable cost per acre thereby rendering the stone gatherer economically feasible to even smaller farmers.

Another object of this invention is to provide a stone gatherer in accordance with the immediately preceding objects and including only two driven components that may be readily driven from a tractor behind which the stone gatherer is being drawn.

Another important object of this invention is to provide a stone gatherer that may be readily transported from one location to another.

A final object of the invention to be specifically enumerated herein is to provide a stone gatherer in accordance with the preceding objects which will conform to conventional forms of manufacture, be of simple construction and easy to use so as to provide a device that will be economically feasible, long lasting and relatively trouble free in operation.

These together with other objects and advantages which will become subsequently apparent reside in the details of construction and operation as more fully hereinafter described and claimed, reference being had to the accompanying drawings forming a part hereof, wherein like numerals refer to like parts throughout and in which:

FIG. 1 is a top plan view of the stone gatherer being towed behind a conventional farm tractor and with the discharge end of the endless conveyor component of the stone gatherer operatively associated with a load bin of a mobile vehicle into which the gathered stones may be discharged;

FIG. 2 is an enlarged top plan view of the stone gatherer;

FIG. 3 is a side elevational view of the assemblage illustrated in FIG. 2;

FIG. 4 is an enlarged fragmentary transverse vertical sectional view taken substantially upon a plane indicated by the section line 4-4 of FIG. 2;

FIG. 5 is a fragmentary vertical sectional view taken substantially upon the plane indicated by the section line 5-5 of FIG. 2; and

FIG. 6 is a fragmentary enlarged vertical sectional view illustrating the manner in which one of the stone elevating and deflecting paddles of the truncated wheel of the stone gatherer is mounted for pivotal movement relative to the truncated cone-shaped wheel.

Referring now more specifically to the drawings, the numeral 10 generally designates a farm tractor which is illustrated in FIG. 1 as a straddling and moving along a windrow 12 of stones to be gathered.

The stone gatherer of the instant invention is schematically illustrated in FIG. 1 as being towed behind the tractor 10 and is generally referred to by the

reference numeral 14. In addition, a mobile load body referred to in general by the reference numeral 16 is being moved along behind the endless conveyor assembly 18 of the stone gatherer 14 for receiving gathered stones discharged from the discharging end of the endless conveyor 18.

From FIGS. 2-4 of the drawings, it may be seen that the stone gatherer 14 includes a main frame referred to in general by the reference numeral 20 having a tow hitch plate 23 at its forward end.

An inwardly downwardly inclined journal sleeve 22 is supported from the left hand side of the main frame 20 in an inconvenient manner such as that illustrated in FIG. 4 and the journal sleeve 22 rotatably journals a stub shaft 24 from whose lower end 27 a stone gathering wheel referred to in general by the reference numeral 26 is supported.

The shaft 24 has a mounting plate 28 supported from its lower end and the stone gathering wheel 26 includes a generally truncated cone-shaped hollow peripheral member 30 closed at its major diameter end by means of an end wall 32, the latter being secured to the mounting plate 28 by means of suitable fasteners 34.

Accordingly, it may be seen that the major diameter end of the stone gathering wheel 26 is closed by means of the end wall 32 and that the minor diameter end of the stone gathering wheel 26 is open. Further, the hollow truncated cone-shaped outer periphery or peripheral member 30 of the wheel 26 is provided with transversely extending and slightly angulated circumferentially spaced slots 38 for purpose to be hereinafter more fully set forth.

The inner surface of the end wall 32 has a plurality of stone elevating plates 40 pivotally secured thereto as at 42 and each of the plates 40 is spring urged by means of a butterfly spring 44 toward the solid line position illustrated in FIG. 6 away from the retracted phantom line position thereof illustrated in FIG. 6.

The right hand side of the main frame 20 of the gatherer 14 includes a ground engaging support wheel 42 journaled on a crank pin portion 44 of a crank shaft 46 oscillatably supported from the frame 20. The shaft 46 includes a crank arm 48 and the frame 20 has a toothed sector plate 50 supported therefrom. An operating lever 52 is pivotally supported from the plate 50 as at 54 and the lever 52 includes a laterally outwardly projecting arm 56 which is pivotally secured as at 58 to the free end of the lever 48. It may further be seen from FIGS. 2 and 3 of the drawings that the free end of the lever 52 includes an operating handle 60 and that a dog element 62 is slidably supported from the lever 52 and spring biased to a position with the dog 62 received between a pair of adjacent teeth of the sector plate 50. However, an operating handle 64 is oscillatably supported from the free end of the lever 52 and is operatively connected to the dog 62 by means of a connecting link 66 whereby the element 62 may be withdrawn from engagement with the teeth of the sector plate 50 at any time the operator of the stone gatherer 14 squeezes the lever or control 64 toward the handle 60. After the dog 62 has been disengaged from the teeth of the sector plate 50, the operating lever 52 may be readily swung between its limits of oscillation in order to adjust the inclination of the stone gathering wheel 26 as desired.

A drive shaft 68 is journaled from the forward portion of the main frame 20 and the forward end of the drive shaft 68 is adapted to be driven from the power take off shaft of the tractor 10.

The rear end of the drive shaft 68 is coupled to the input shaft 70 of a gear reduction assembly 72 having an output shaft 76 drivingly connected to a shaft 80 journaled from the rear lower portion of the frame 20 by means of an endless flexible chain 82 trained over pulley wheels 84 and 86 carried by the shafts 76 and 80. However, the gear or sprocket wheel 86 is drivingly coupled to the shaft 80 by means of a releasable clutch assembly 90.

The shaft 80 is journaled from the main frame 20 by means of depending support bracket means 96 and it may be noted from FIGS. 1 and 2 of the drawings that the shaft 80 is inclined forwardly away from the open side of the lower periphery of the wheel 26.

A fluted roller 94 is mounted on the shaft 80 for rotation therewith and it is of course to be understood that forward movement of the tractor 10 in order to tow the stone gatherer 14 there behind will result in the roller 94 being rotated in a counterclockwise direction as viewed in FIGS. 3 and 5 of the drawings. Accordingly, with the fluted roller 94 aligned with the windrow of stones 12, forward movement of the tractor 10 to move the stone gatherer 14 along the windrow 12 will result in the fluted roller 94 engaging and deflecting the windrowed stones into the lower periphery portion of the open minor diameter end of the wheel 26. Of course, some dirt will also be deflected into the lower periphery of the wheel 26, but the slots 38 formed in the periphery member 30 of the wheel 26 will allow smaller particles of dirt to fall from the wheel.

A shield plate 100 is supported from the frame 20 immediately adjacent and slightly rearward of the last marginal portion of the wheel 26 with the plate 100 positioned to keep any gathered stones within the wheel 26 from being discharged outwardly of the minor diameter end of the wheel 26 until such time as the stones are elevated to the level of the upwardly opening notch or window 102 formed in the plate 100.

The stone elevating paddles 40 engage the stones collected within the lower periphery of the wheel 26 and elevate those stones to the level of the window 102 each time one of the paddles 40 swings from the lower periphery portion of the wheel 26 up to the level of the window 28. Of course, the paddles 40 then urge the gathered stones outwardly of the window 102 for falling onto the inlet end 104 of an endless flexible conveyor assembly 106 supported from the rear of the frame 20 in any convenient manner. The endless conveyor assembly 106 includes a hydraulically actuated drive motor 108 and it is to be noted that the drive motor 108 may be readily powered by an operatively connecting hydraulic flow lines between the motor 108 and the hydraulic system (not shown) of the tractor 10.

The endless conveyor assembly 106 may be of any desired type. The conveyor assembly 106 extends generally longitudinally of the stone gatherer 14 and its rear end is inclined upwardly so that the load bed 16 may be positioned under the elevated discharge end of the conveyor assembly 106.

The flutes on the roller 94 are designated by the reference numeral 110 and extend longitudinally thereof on the end thereof remote from the wheel 26. However, on the end of the roller 94 adjacent the wheel 26, the flutes 94 are spiraled about the roller 94. In this manner, there is greater assurance that all of the stones within the windrow 12 will be deflected into the stone gathering wheel 26.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

What is claimed as new is as follows:

1. A stone gatherer including a main frame, a hollow generally truncated cone-shaped wheel journaled from said frame for rolling along the ground surface over which said frame is advanced, the major and minor diameter axial ends of said wheel being closed and open, respectively, means supported from said frame for engagement with and laterally deflecting windrowed stones along which said frame is advanced into said open minor diameter end of said wheel, the axis of rotation of said wheel lying in a substantially vertical plane normal to the direction of intended movement of said frame and said axis being inclined relative to the horizontal an amount substantially equal to the angle of displacement of the slant height of the wheel relative to the wheel center axis with the lowermost slant height of the wheel horizontally disposed, an upstanding shield plate supported from said frame and extending across and closing the rear lower quadrant portion of the open minor diameter end of said wheel, the interior of said wheel including circumferentially spaced lift panels generally paralleling and adjacent radial planes of said wheel, the outer periphery of said wheel being closed by a generally frustoconical peripheral member having a plurality of dirt and small pebble slots formed therein generally paralleling but slightly inclined relative to diametric planes of said wheel with the slots inclined slightly relative to said diametric planes in a manner such that the ends of the slots in the lower peripheral portion of the wheel forwardmost relative to the direction of the intended movement of the frame are adjacent the minor diameter end portion of the wheel.

2. The combination of claim 1 wherein said lift panels are pivotally supported from the closed end of said wheel for oscillation about generally radial axes and are spring biased toward a position generally normal to radii of said wheel normal to said radial planes.

3. The combination of claim 1 wherein the stone deflecting means comprises a powered rotary ground level roller inclined forwardly and outwardly from the rear portion of the ground contact area of the lower periphery of the wheel with the roller extending outward of the open side of the wheel, and motor means supported from said frame and drive means drivingly connected to said roller for rotating the latter in a direction to advance the lower periphery thereof in the direction of advancement of said stone gatherer.

4. The combination of claim 3 wherein said roller includes longitudinally extending and radially outwardly projecting flutes.
